[57] CLAIM

The ornamental design for a counter top water purifier, as shown and described.

DESCRIPTION

FIG. 1 is a perspective view taken from the top, front and right side of a counter top water purifier showing my new design;

FIG. 2 is a front elevational view thereof;

FIG. 3 is a right side elevational view thereof, the left side being a mirror image of the right side shown;

FIG. 4 is a rear elevational view thereof with the bottom right corner broken away for convenience of illustration;

FIG. 5 is a top view thereof; and

FIG. 6 is a bottom view thereof.
